UNITED STATES PATENT OFFICE.

HUGH CARMICHAEL SMITH, OF UNION CITY, TENNESSEE.

DESIGN FOR A BOTTLE.

Application filed June 7, 1926. Serial No. 17,964. Term of patent 14 years.

To all whom it may concern:

Be it known that I, HUGH CARMICHAEL SMITH, a citizen of the United States, residing at Union City, county of Obion, State of Tennessee, have invented a new, original, and ornamental Design for Bottles, of which the following is a specification, reference being had to the accompanying drawing, forming a part thereof.

In the drawing:—

Figure 1 is a view of the bottle in side elevation, showing my new design.

Figure 2 is a horizontal cross section of the bottle shown in Figure 1 on substantially the line 2—2 of Figure 1.

Figure 3 is a horizontal cross section of the bottle shown in Figure 1 on substantially the line 3—3 of Figure 1.

I claim:—

The ornamental design for a bottle, as shown.

HUGH CARMICHAEL SMITH.
